UNITED STATES PATENT OFFICE.

ANDREAS WILHELM SCHWARZLOSE, OF CHARLOTTENBURG, GERMANY.

TOGGLE-JOINT BREECH MECHANISM.

1,070,633.

Specification of Letters Patent. Patented Aug. 19, 1913.

Application filed February 8, 1913. Serial No. 747,104.

To all whom it may concern:

Be it known that I, ANDREAS WILHELM SCHWARZLOSE, a subject of the German Emperor, and resident of Charlottenburg, Germany, have invented certain new and useful Improvements in Toggle-Joint Breech Mechanism, of which the following is a specification.

This invention relates to a breech mechanism with knuckle joint for automatic firearms which is characterized in that the devices for closing the mechanism and for firing are housed in the branches of the knuckle joint themselves. In lieu of the actual breech block containing the firing pin and the firing spring, a short guide head has been provided in the present construction which only serves as a fulcrum for the forward branch of the knuckle joint and for guiding the latter in the longitudinal direction whereby the entire length of the mechanism is very considerably reduced. By this as well as owing to the fact that special guides for the main or closing spring are dispensed with in the breech casing, not only a greater simplicity of the mechanism is obtained but also such a great saving in weight arrived at that the members or branches of the knuckle joint can be made considerably stronger and more lasting than this was possible until now without the actual weight of the fire-arm being excessive. Besides in fire arms which are to be shoudered the joint which during the shot oscillates backward toward the eye of the shooter is kept away from the eye.

The novel breech mechanism can be employed for hand fire-arms as well as for machine guns and allows of its being constructed as a mechanism operated by the gas pressure and as a mechanism operated by the recoil.

Figures 1-12 of the drawing first show the breech mechanism in combination with a hand rifle with a fixed barrel, in this drawing: Fig. 1 shows a vertical longitudinal section of the breech mechanism in a closed condition, while Fig. 2 shows same in an open position. Fig. 3 is a cross section of same along a line 1-2 of Fig. 1 and Fig. 4 a cross section of same on line 3-4 of Fig. 1. Fig. 5 shows side, front and top views of a breech block used herewith. Fig. 6 shows similar views of the front member of the knuckle. Fig. 7 shows side and top views of the rear member of the knuckle. Fig. 8

shows front and side views of a cam used herewith. Fig. 9 shows front and side views of the firing pin. Fig. 10 shows front and side views of a tumbler used herewith. Fig. 11 is a side view of a cartridge extractor. Fig. 12 is a detail of a certain pivot pin.

In the embodiment shown the barrel *l* is rigidly connected with the breech casing *h* by means of a screw connection and both parts are rigidly connected in the well known manner with the rifle stock. The guide head *V* (Fig. 5) comprises a substantially segmento-cylindrical part *v* which is provided with a flat surface *v*⁶ at the barrel contacting end and is provided at this part with a depression or recess *v*⁷ intended to receive the head of the cartridge. It comprises besides the two lateral ledges *v'* which are guided in a rectilinear manner in the longitudinal grooves *h'* of the breech casing. The ledges are provided on their inside with arc shaped projections *v*² which when the breech mechanism is put together engage the two similarly shaped milled out parts *s*³ of the front branch or part of the knuckle joint *a* (Fig. 6) in such a manner that they couple the joint in a rotary manner with the guide head. The knuckle joint of the mechanism is provided for this purpose with a half-round depression *s*¹ which rotates over the part *v*. The center of relative movement or fulcrum *c* (Figs. 1 and 2) between the knuckle joint and the guide head is positioned in the example shown at the level of the head of the cartridge in the barrel. The half cylindrical part *v* is provided with a central bore *v*⁸ through which the cylindrical projection *s*⁶ of the front branch of the knuckle joint passes. This projection, when the mechanism is closed (Fig. 1) is closely applied with its front surface against the head of the cartridge in the barrel; it thus receives during the firing the back pressure and transmits it directly to the knuckle joint of the mechanism without bringing pressure against the guide head *V*.

The knuckle joint *s* is provided with a longitudinal bore *s*⁴ which receives the firing spring *f* and the firing pin *b'* which members are inserted in the front arm from the rear. The point of the firing pin, which is made in one piece, (Fig. 9) is positioned so as to be slightly eccentric to the shaft *b'* and passes through the projection *s*⁶ when the shot is fired (Fig. 1).

The firing pin is cocked by the rod k (Figs. 1 and 2) which at its front part places itself with its nose k' in front of the stud b^2 of the firing pin and at its rear part carries two lateral studs k^2 which are seized by the notches g^5 of the rear branch g of the knuckle joint when the mechanism is opened and thus pulled back (Fig. 2). The tumbler n (Fig. 10) serves to hold the firing pin in a cocked condition; it is mounted in the front branch of the knuckle joint so as to be able to rotate around the pin t and its hook n^2 places itself in front of the notch b^3 of the firing pin when the latter is pulled back (Fig. 2). The sleeve o which bears at its front part against the firing spring f and at its rear end against the upper arm of the tumbler and at the same time guides the firing pin, continuously presses the front arm of the tumbler upward.

The front branch s of the knuckle joint is constructed in such a manner that when the breech mechanism is open, its two extensions s^5 project at the top beyond the front surface of the guide head (Fig. 2).

The eye s^2 of the branch s of the knuckle joint is connected in the well known manner by means of the ears g^2 and the bolt b with the eye of the rear branch of the knuckle joint (Fig. 7) which in turn oscillates around the cam shaft d (Fig. 8) in the breech casing. The branch g of the knuckle joint receives in its longitudinal bore g^4 the main spring f' which through the instrumentality of the shaft d and the sleeve i is connected with the breech casing in such a manner that it is tensioned when the branches of the knuckle joint oscillate upward (Fig. 2) and closes the breech mechanism again automatically after the counter pressure has ceased. The shaft d is provided to this effect with a tensioning cam d' against which the spring sleeve i bears which spring sleeve is guided at its front part by the pin e of the branch of the knuckle joint. The shaft d is milled out to form a recess d^3 wherein the head of the sleeve i may rest and by means of this recess the head of the sleeve moves backward relatively to the branch when the mechanism is closed under the influence of the spring f' . The handle piece d^2 is fixed to one end of the shaft d and serves to actuate the shaft and bears in such a manner against an abutment h^5 extending from one side of the breech casing (Fig. 1) that the shaft, when the breech mechanism is opened cannot rotate backward under the pressure of the spring f' . When the breech mechanism is put together the shaft d is inserted from the right hand side of the breech casing, the handle being turned forward and the main spring being pushed forward, and is thereafter rotated backward against the shoulder h^5 . The branch g of the knuckle joint is provided on its right hand side with a

cut away portion g^3 which allows the passage of the tensioning cam, the breech casing being provided in a similar manner with a similar cut away portion.

In order to be able in the embodiment shown to annul the action of the main spring on the breech mechanism when the fire arm is to be used as a hand loader, the shaft d is rotated forward by means of its handle d^2 to such an extent that the tensioning cam d' springs behind the beveled part i' of the head of the sleeve (Fig. 2 dot and dash lines). This being so the shaft, when the knuckle joint oscillates upward is carried along by the latter so that it rotates in the breech casing and is unable to exert any closing action upon the breech mechanism.

It will be obvious, from the inspection of the drawings, that during automatic action the cam d' is in such position that it cannot engage the beveled part of the sleeve head.

In connection with the invention the extractor illustrated in Fig. 11 and indicated generally at z' is used, it is not deemed necessary to specifically describe this extractor as the same does not form a specific part of the present invention.

Slidably mounted in the casing is a sear rod a' to which is connected a trigger z . At w^3 is a pivot which passes through the sear rod a' and through a sear pawl w provided adjacent its forward end with a lug or hook w' . This sear rod is provided at its sides with lateral extending ribs or ledges a^3 and these ledges engage in grooves a^5 formed in the breech casing, the ledges and grooves serving to guide the sear rod. At the rear end of the sear rod there is provided a stud p .

The release of the cocked firing pin is produced by the sear rod a' (Figs. 1 and 2) which when the trigger z is pulled glides slightly backward in the breech casing. The hook w' of the sear pawl w which is pivotally connected with the sear rod, carries with it the lower arm of the tumbler n so that the front arm of the latter slides from the notch b^3 of the firing pin thus allowing the firing spring to throw the firing pin forward (Fig. 1). The sear rod engages with its two lateral ledges a^3 corresponding milled out grooves of the breech casing (Fig. 3) so that it can move backward and forward in a straight line in the longitudinal groove h^4 of the latter. When the breech mechanism is closed the sear rod is positioned above the uppermost cartridge contained in the magazine and thus serves at the same time as a magazine lock. When the breech mechanism is opened the guide head, in the latter part of its backward motion, strikes with its lower transverse part against the shoulder a' of the sear rod whereby the latter is pulled back until it is positioned behind the cartridge magazine thus freeing the up-

5 permost cartridge of the magazine with a view to its introduction into the barrel (Fig. 2). As soon as the sear rod during this motion takes up a position behind the magazine, its stud p strikes against the rear end of the groove h^4 and compresses the spring f^2 (Fig. 1) which is housed in the sear rod and in this manner acts at the same time as a buffer spring, while the front end of the 10 spring is applied against the sear pawl w thus yieldingly and constantly pushing the latter upward. As readily seen the front end of the sear pawl when the breech mechanism is opened, places itself in the way of motion of the extracted cartridge case and 15 ejects the latter in an upward direction (Fig. 2). Upon the rear end of the sear rod there are provided inclined surfaces a^6 which, when the sear rod moves backward 20 engage the incline lugs a^7 formed in the bottom of the groove h^4 . On the under side of the guide head b there is provided a notch b^4 and on the forward end of the sear rod is a hook a^2 while a stud a^4 is also formed 25 on said rod adjacent the pivot w^3 .

The sear rod while moving backward is at the same time slightly lifted upward by the rear terminal surfaces of the ledges a^3 which engage inclined surfaces of the 30 breech casing, while the hook a^2 engages the notch v^4 (Fig. 5) of the guide head v . When the breech mechanism is closed the guide head, as readily seen, also pulls the sear rod again forward until the studs a^4 35 of the rod place themselves under the downwardly inclined guides of the breech casing and press the rod slightly downward so that the hook a^2 leaves again the guide head. The sear rod is thus disengaged from the 40 breech mechanism which continues its forward movement, and stops in the position shown in Fig. 1, while the hook w' of the pawl w again springs in front of the lower arm of the tumbler n after the breech mechanism has been entirely closed.

The action of the main spring f' on the 45 knuckle joint of the breech mechanism is adjusted in such a manner that when the breech mechanism is opened (Fig. 2) it is incapable of throwing the latter forward by itself. It is therefore not necessary when 50 opening the fire arm by hand that the marksman when he pushes the cartridges into the magazine or when he loads the rifle with separate cartridges, holds the breech mechanism. However, when automatic firing is practiced the buffer action of the spring f^2 throws the breech mechanism forward with such a violence that the main 55 spring is carried off the dead center and that the breech mechanism is thrown forward into the closing position without any 60 interruption.

In order to allow of the firing pin and the 65 tumbler and the firing spring to be easily

removed from the knuckle joint of the breech mechanism for cleaning purposes, the tumbler n is secured in the branch s by means of the pin stirrup t (Fig. 12). The second branch of this stirrup passes through 70 a hole bored in the hinge pin b (Figs. 1 and 2) while the hook t' springs in front of a corresponding notch of the hinge pin. As the pin b can only be slid out toward the side from which it was inserted, the arrangement described fixes the pin stirrup as well as the hinge pin in such a manner that they can be taken apart by hand. After the separation of the branches s and g has been effected, the firing pin and its 80 firing spring, the spring sleeve and the tumbler can then be removed in a cocked condition as a whole from the knuckle joint branch.

Having now fully described my said invention, what I claim and desire to secure by Letters Patent, is:

1. In a breech mechanism of the kind described the combination with the breech casing; of a knuckle joint and means for closing the breech mechanism and for firing, said means being mounted in the branches of the knuckle joint themselves, substantially as and for the purpose set forth.

2. In a breech mechanism of the kind described, the combination with the breech casing; of a knuckle joint, a main spring adapted to close the breech mechanism and housed in the rear branch of said knuckle joint, a firing pin, a firing pin spring, and means adapted to cock and lock the said firing pin and spring, the said firing pin, spring and their controlling means being mounted in the front branch of said knuckle joint, substantially as and for the purpose set forth.

3. In a breech mechanism of the kind described the combination with the breech casing; of a knuckle joint, a main spring adapted to close the breech mechanism and housed in the rear branch of said knuckle joint, a shaft adapted to hingedly connect the rear end of the said rear branch of said knuckle joint with the said breech casing, means including a cam on said shaft for causing the said shaft to tension the said main spring under normal conditions, said cam being adapted to be turned forward to prevent closing of the breech.

4. In a breech mechanism of the kind described the combination with the breech casing; of a knuckle joint, a main spring adapted to close the breech mechanism and housed in the rear branch of the said knuckle joint, a shaft hingedly connecting the rear end of the said rear branch of said knuckle joint with the said breech casing, a cam provided on said shaft and adapted to tension the said main spring during the opening motion of the mechanism, means for ro-

tating the said shaft to move the cam forward and prevent said main spring from expanding when the mechanism is open, whereby the fire-arm is held on safety, and 5 a handle on said shaft to rotate the shaft backward when the mechanism is closed and thereby open said mechanism.

5. In a breech mechanism of the kind described the combination with the breech 10 casing; of a knuckle joint including front and rear arms, a main spring adapted to close the breech mechanism and housed in

the rear arm of the said knuckle joint, a firing pin housed in the front arm of said knuckle joint and means carried by said front arm to reciprocate said pin, said means including a firing spring arranged to move the pin in one direction. 15

In testimony whereof I have hereunto set my hand in presence of two witnesses. 20

ANDREAS WILHELM SCHWARZLOSE.
